(57) **CLAIM**

The ornamental design for a dashboard for automobile or replica thereof, as shown and described.

DESCRIPTION

FIG. 1 is a rear perspective view of an embodiment of a dashboard for automobile or replica thereof in accordance with the present design;

FIG. 2 is a rear, left perspective view of FIG. 1;

FIG. 3 is a front, right perspective view of FIG. 1;

FIG. 4 is a top plan view of FIG. 1;

FIG. 5 is a rear, right perspective view of FIG. 1;

FIG. 6 is a partial left elevation view of FIG. 1; and,

FIG. 7 is a partial right elevation view of FIG. 1.

The features depicted in evenly spaced broken lines depict environmental structures that form no part of the claimed design of the dashboard for automobile or replica thereof.

1 Claim, 7 Drawing Sheets
